UNITED STATES PATENT OFFICE.

WILLIAM L. R. EMMET, OF SCHENECTADY, NEW YORK, ASSIGNOR TO GENERAL ELECTRIC COMPANY, A CORPORATION OF NEW YORK.

ENFORCED-FLOW ELASTIC-FLUID TURBINE.

932,849.

Specification of Letters Patent. Patented Aug. 31, 1909.

Application filed January 21, 1907. Serial No. 353,195.

To all whom it may concern:

Be it known that I, WILLIAM L. R. EMMET, a citizen of the United States, residing at Schenectady, county of Schenectady, 5 State of New York, have invented certain new and useful Improvements in Enforced-Flow Elastic-Fluid Turbines, of which the following is a specification.

The present invention has for one of its 10 objects to improve the economy of the well-known Curtis type of elastic-fluid turbine.

A further object is to provide a turbine of an improved construction for attaining the first-mentioned object.

15 In carrying out the invention the turbine is provided with as many stages as are necessary to effectively extract the energy from the steam or other elastic fluid. The stages may perform equal or unequal amounts of 20 work as best suits the requirements. Between the initial source of supply and the first stage a certain predetermined drop in pressure exists, and between said stage and each of the succeeding stages the pressure

25 drops step by step. In practice I find it desirable to have a greater pressure drop in the first stage than in each of the succeeding stages, so as to reduce the rotation losses, and also to avoid imposing undue strains on 30 the wheel casing and the diaphragm or partition between the first and second stages. In the high-pressure stages only a portion of the wheel buckets are active while in one or more of the low-pressure stages all of the 35 wheel buckets are active. The passages in the expanding nozzle discharging steam into the first stage cover only a portion of the wheel arc and are arranged to convert an amount of pressure represented by the drop

40 in pressure between the source of supply and the first stage compartment into velocity and to discharge the fluid against the wheel buckets. The pressure of the fluid stream at the discharge end of the nozzle may be the 45 same as the stage compartment pressure so that the fluid acts solely by impact, or the pressure may be slightly above the stage compartment pressure so as to compensate for the losses due to the friction of the fluid 50 stream on the buckets. In other words there may be a slight drop in pressure of the fluid stream between the point where it enters and leaves the working passages of the wheel. It is desirable to make this drop in pressure 55 small since if the nozzle end pressure is

materially greater than the stage compartment pressure, there will be excessive leakage through the clearances between the relatively moving parts. Any fluid escaping through the clearances in a given stage is lost to that 60 stage because it freely enters the chamber or compartment in which the wheel is located, provision being made to equalize the pressures on opposite sides of the wheel to prevent end thrust.

65 The velocity of the fluid stream is abstracted in each stage by successive operations, suitable intermediate buckets being located between the rows of wheel buckets to receive the fluid from one row and discharge it against the next at the proper angle. In the present embodiment of the invention two rows of wheel buckets with a partial row of intermediates are sufficient for the purpose, the said intermediates being 70 located directly in line with the nozzle. Where the velocity of the fluid stream is greater than in the present case, I may provide a greater number of rows of wheel buckets and one or more additional rows of 75 intermediates buckets in each stage. The same arrangement of parts is preserved in the later high-pressure stages, the arc covered by the nozzle and the intermediates gradually increasing by stages toward the 80 exhaust to compensate for the increased volume of motive fluid due to its decreased pressure.

85 In one or more of the low-pressure stages the arrangement is entirely different. Here 90 the nozzle extends entirely around the wheel and casing and all of the buckets adjacent thereto are active. For normal load conditions, the motive fluid instead of expanding down to substantially the exhaust pressure 95 of the stage in the nozzle, is expanded only partially down, the remainder of the expansion taking place in the wheel and intermediate buckets, whereby the energy of the motive fluid is converted into useful work by 100 the impact of the fluid on the buckets and also by the reaction of the fluid on the buckets as it flows from one row to the next. Since the nozzle end pressure is materially 105 above that of the fluid stream exhausting from the buckets it follows that the flow will be enforced by an amount determined by the pressure difference between the inlet and the exhaust. The amount of this pressure drop, where only the initial, or the initial and cer- 110

tain of the later stages are governed will vary to a greater or less extent with load changes, it being greatest at heavy loads. From this it follows that at moderate loads 5 the stage or stages thus arranged will work more after the fashion of a pure impulse machine while as the load increases to a maximum the stage or stages will work more and more as a combined impulse and reaction machine. In order to effectively abstract a large proportion of the energy in the fluid stream in the low pressure stage or stages I find it desirable to provide a greater number of rows of buckets in said stage or 10 stages than in the high pressure stage or stages.

It is apparent that with a nozzle end pressure so much higher than the exhaust pressure of the wheel that unless special 20 provision is made there will be excessive leakage past the wheel. To prevent this leakage and also to obtain the full benefit of the motive fluid I make the nozzle a complete annulus and all of the wheel buckets 25 will therefore be active. The annular nozzle is divided by partitions which are thin at the discharge end and serve with the side walls to properly direct the motive fluid. Under certain conditions these passages may 30 be non-expanding in character or they may be expanding. Between the rows of wheel buckets are annular rows of intermediate buckets, all of which are active. These are carried by bases supported by the turbine 35 casing, the said bases acting to prevent the free passage of motive fluid past the wheel buckets and cause it to flow through the bucket spaces and perform useful work by impulse and reaction.

40 Obviously the arrangement described creates a heavy end thrust on the shaft because the effective pressure on the nozzle side of the wheel is that due to the area of the wheel times the nozzle end pressure, while 45 on the other side it is that due to the area of the wheel times the exhaust pressure of the stage. I prefer to partially balance the thrust due to one or more wheels by that due to one or more other wheels oppositely 50 arranged. This construction is particularly adapted for vertical shaft machines, since the wheel exerting the greater thrust can be arranged in a manner tending to lift the weight of the shaft and revolving elements 55 carried thereby, and thus relieve the step bearing. Care should be taken to so arrange the parts that the upward thrust is never quite sufficient to overcome the downward thrust and the weight of the revolving element, the latter commonly including the rotating member of a dynamo-electric machine. In carrying out this feature of my invention a vertical shaft is provided which is surrounded by a casing divided into wheel or 60 stage compartments by diaphragms. In the

high-pressure stage compartments the direction of steam flow is downward while in the first of the low-pressure stage compartments it is upward and in the second it is downward, the two stage compartments working 70 in series. That is to say, the steam flows first through one, then reverses and flows through the other to the exhaust. In order to provide for this change in direction of the steam in its passage through the stage compartments, the casing has vertically disposed conduits some of which receive steam from a high pressure stage compartment and supply it to one of the annular or total flow stage compartments while the remaining 75 conduits receive fluid from the said annular or total flow stage compartment and after reversing its direction of motion with respect to the shaft discharge it downwardly to the nozzle of the last stage. By varying 80 the pressures existing at the ends of the nozzles in certain stages for a given load condition, the lifting effect on the shaft can be made greater or less.

The admission of fluid to the turbine is 90 controlled by a valve mechanism under the control of a speed governor. As shown separately actuated valves are employed. I may use stage valves between the high pressure stages if desired, so as to vary the number of 95 active nozzles or nozzle sections. As the buckets in the low pressure stages have to handle a large volume of fluid, it is impracticable to make the expansion on one side only, as in the usual construction, by 100 slanting the covers of the buckets, because the angle is so great that the motive fluid will not properly fill the bucket spaces. To overcome this I step the face of the wheel and also that of the adjacent surface of the 105 casing and mount the buckets on the steps thus formed. The covers and the portions of the bases between the buckets diverge, the angle of inclination to a plane parallel with the shaft being the same in both cases.

In the accompanying drawings which are 110 illustrative of one of the embodiments of my invention, Figure 1 is a quarter longitudinal section of a turbine having high pressure partial flow stages and low-pressure total 115 flow or annular stages; Fig. 2 is a cross-section looking down on the diaphragm just above the first annular stage, with certain of the parts broken away; Fig. 3 is a partial axial section showing a conduit for conveying motive fluid from one annular stage to another; Fig. 4 is a cross-section taken just above the last diaphragm; and Fig. 5 is a detail view showing a step bearing for supporting the vertical shaft.

120 1 represents an upright shaft having a number of high pressure disk wheels and two or more low pressure wheels 3 and 4, said wheels and shaft together forming the rotor 125 of the turbine. The wheels 3 and 4 are pro-

vided with wide rims or drums for carrying a number of rows of buckets. The turbine wheels are inclosed by a sectional casing and are located in stage compartments separated 5 one from the other by diaphragms. The upper diaphragm 5 is made somewhat smaller than the other high pressure diaphragms owing to the high pressure to which it is subjected. It is supported by an internal 10 shoulder 6 on the inside of the casing, the said shoulder also containing stage nozzles 7. The casing 8 for the high pressure stages forms one section of the whole and rests on the section 9, the latter being mounted on a 15 base section 10 containing a chamber communicating with the atmosphere, condenser or other exhaust. The base section usually but not necessarily supports the step bearing for the shaft which takes care of any 20 desired percentage of the weight and also any excess thrust due to the arrangement of the parts. The diaphragm 11 between the high and low pressure stage compartments rests on a shoulder 12 formed on an internal projection 13 on the casing section 9. This 25 projection contains two sets of passages or conduits 14 and 15, the former supplying motive fluid to next to the last wheel and the latter to the last wheel. The conduits 14 30 receive motive fluid from the annular chamber 16 bounded by the periphery of the diaphragm and the inner wall of the upper section of the casing and discharge it to the annular chamber 17 formed in the internal 35 projection 13. By reason of this chamber the pressure of the fluid from the several conduits is first equalized and then fed to all of the nozzle sections.

The conduits 15 receive motive fluid from 40 the chamber 18 formed above the first low pressure wheel and discharge it in multiple into the annular chamber 19 that is also formed in the internal projection 13 of the casing. This annular chamber equalizes the 45 pressures of the several streams issuing from the conduits 15 and also supplies it to all of the nozzle sections of the last wheel. The casing is provided with a head 20 which supports the valve chest 21 and also the packing 50 22. Between the shaft and each of the diaphragms is a self aligning packing 23 to prevent the escape of fluid.

Admission of fluid to the turbine is controlled by the separately actuated valves 24, 55 the latter acting under the control of a suitable governing mechanism. I have not illustrated the stage valves which respond automatically to pressure changes because they are not in the plane of the section. 60 When one of the admission valves opens it supplies fluid to the chamber 25 which in turn delivers it to one or more sections of the inlet nozzle 26. This nozzle is arranged to convert a certain amount of pressure of the 65 fluid into velocity and discharge it against

the buckets adjacent thereto. The nozzle covers only a portion of the circumference of the wheel and the pressure of the fluid issuing therefrom is substantially that of the stage compartment in which the wheel 70 rotates.

Intermediate buckets 27 are located between the wheel buckets 28 and serve to reverse the direction of flow of the fluid as it passes from one row to another. These 75 buckets cover an arc somewhat greater than the nozzle in order to take care of the spill therefrom. In the stage compartment and in close proximity to the under side of the wheel is a segment 29 of a ring, which roughly conforms to the shape of the wheel near the periphery and acts to prevent the motive fluid from rebounding on a fixed part of the casing and striking the wheel in a manner to oppose rotation. The ring is 80 supported from the adjacent diaphragm by upright supports 30. The same arrangement is followed in each of the high pressure stage compartments with the exception that the arcs covered by the nozzles and 85 intermediates successively increase as the pressures in the stages decrease. The cross-sectional areas of the nozzles and bucket spaces increase of course to take care of the increased volume of motive fluid at the decreased pressure. 90

In Fig. 5 is shown a step bearing 35 mounted in a suitable casing 36 supported by the base of the machine or other support and a guide bearing 37. 100

In the Curtis type of turbine, over which my invention is an improvement, provision is made for overcoming losses due to friction, eddy currents, etc. by slightly enlarging the bucket spaces over that actually required to convey the motive fluid. This enlargement of the bucket spaces results in a small drop in pressure between the inlet and discharge of the working passage in a given stage, but this is insufficient to perform any actual work in driving the bucket wheels. In my improved construction, however, provision is made in the low pressure annular or total flow stages for causing the expansion of the steam in the bucket spaces to not only compensate for the frictional retardation but actually to perform work by reason of the reaction effect as the pressure decreases step-by-step in the bucket spaces of the wheel and intermediates. In these buckets the velocity steps are small and are also equal under predetermined load conditions. 110 115 120

In accordance with the provisions of the patent statutes, I have described the principle of operation of my invention together with the apparatus which I now consider to represent the best embodiment thereof; but I desire to have it understood that the apparatus shown is only illustrative, and that 125 130

the invention can be carried out by other means.

What I claim as new and desire to secure by Letters Patent of the United States, is,—

- 5 1. An elastic fluid turbine comprising a plurality of stage compartments working at different pressures, a nozzle for a high pressure stage which converts the available pressure thereof into velocity, and whose end pressure is substantially the same as that of the exhaust from the stage compartment, wheel buckets coöperating therewith to abstract the velocity, an annular nozzle for a low pressure stage which partially converts
- 10 15 the available pressure of the stage into velocity and has an end pressure considerably in excess of that of the exhaust from the stage compartment, a wheel having rows of buckets, all of which are active, a complete annular row of intermediate buckets, the said rows of intermediate and wheel buckets alternately converting the pressure of the fluid into velocity and abstracting it as the fluid flows through the stage compartment,
- 20 25 and means for causing the fluid to flow in a reverse direction through certain of the stage compartments.

2. An elastic fluid turbine comprising a plurality of stage compartments working at different pressures, a nozzle which converts the available pressure of a high pressure stage into velocity, wheel and intermediate buckets which fractionally abstract the velocity of the fluid received from the nozzle, a wheel for the buckets which is balanced as to fluid pressures, an annular nozzle for a low pressure stage which converts only a certain percentage of the available stage pressure into velocity, wheel and intermediate buckets arranged in rows, all of which are active and coöperate with the nozzle to abstract the velocity from the fluid due to the nozzle and also to alternately create velocity and abstract it as the fluid flows toward the exhaust, and means for causing the fluid to flow in a reverse direction through certain of the stage compartments.

3. An elastic fluid turbine comprising a plurality of stages working at successively decreasing pressures, nozzles for the high pressure stages that convert the available pressure of each of the high pressure stages into velocity, wheel buckets coöperating therewith which abstract the energy of the fluid without imparting velocity thereto, annular nozzles for the low pressure stages which convert only a limited portion of the available pressure of each stage into velocity, wheel and intermediate buckets arranged to abstract the velocity of the fluid as received from the annular nozzles and also to create velocity and abstract it by successive steps as the fluid flows through the stage, wheels for the buckets, supports for the low pressure intermediate buckets, the wheels and

supports coöperating to prevent the fluid from flowing from a point of high to a point of low pressure without passing through the bucket spaces, and means for causing the fluid to flow in a reverse direction through certain of the low pressure stages.

4. An elastic fluid turbine comprising a casing, high and low pressure diaphragms for dividing the casing into stage compartments, bucket wheels for the high pressure stage compartments, bucket wheels for the low pressure stage compartments having a greater number of rows of buckets than those of the high pressure stages, expanding nozzles for high pressure stages, intermediate buckets therefor, the nozzles and buckets covering less than the full circumference of the wheel, annular nozzles for the low pressure stages which convert a portion only of the available stage pressure into velocity, intermediate low pressure buckets, the wheel and intermediate buckets of the low pressure stages being constructed and arranged to work by impact of the motive fluid under certain load conditions and to work by impact and reaction under other load conditions, and means for causing the fluid to flow in a reverse direction through certain of the low pressure stages.

5. An elastic fluid turbine comprising a plurality of stages through which the motive fluid flows one after the other in series, buckets therefor, fluid discharging devices for the different stages, the buckets and said device of one of the intermediate pressure stages being reversed with respect to those of the remaining stages, a casing for the turbine, an annular chamber in the casing which is in communication with said reversed device, conduits formed in the casing which convey motive fluid exhausting from the preceding stage to said chamber, and other conduits in the casing for conveying motive fluid exhausting from the reversed stage to the next stage.

6. An elastic fluid turbine comprising a casing, diaphragms for dividing the casing into a plurality of stages each containing a bucket wheel and fluid discharging means, the motive fluid flowing through said stages in series and one of said stages being reversed in position with respect to the others, a wall within the casing surrounding the reversed stage and coöperating with the two adjacent diaphragms to inclose said stage, and conduits arranged in the space between the wall and the casing for conveying motive fluid to and from said stage.

7. An elastic fluid turbine comprising partial flow impact stages, low pressure stages acting by impulse and reaction, nozzles for the high pressure stages that convert the available stage pressure into velocity, wheel buckets acted upon by motive fluid from the nozzles, annular nozzles for

the low pressure stages that convert only a portion of the available stage pressure into velocity, one of said annular nozzles discharging motive fluid in a direction opposite to the others to reduce the resultant end thrust on the shaft, and conduits for conveying motive fluid through the stages in series.

8. An elastic fluid turbine comprising a plurality of stages each containing a bucket wheel and a fluid discharging means, one of said stages being reversed in position with respect to the others, conduits formed in the casing which receive fluid from one stage, 10 convey it past the reversed stage in a given direction and deliver it to said means, and a second set of conduits formed in the casing and arranged in alternate relation to the first set for receiving fluid exhausting 15 from the reversed stage, conveying it past said stage in the opposite direction to the flow through the first set of conduits, and delivering it to another stage.

9. An elastic fluid turbine comprising a plurality of stages, each containing a bucket wheel and a sectionalized fluid discharging device, one of said stages being reversed in position with respect to the others, annular chambers which equalize the pressure of the 25 fluid supplied to certain of the discharging devices, a conduit which receives fluid from one stage and discharges it into one of the annular chambers, and a second conduit which receives the fluid exhausting from the 30 reversed stage, conveys it past said stage and discharges it into a second annular chamber.

10. An elastic fluid turbine comprising a plurality of stages, each containing a bucket 40 wheel and a sectionalized fluid discharging device, one of said stages being reversed in position with respect to the others, annular chambers which equalize the pressure of the fluid supplied to certain of the discharging 45 devices, a plurality of conduits which receive fluid from one stage, convey it past the reversed stage and discharge it into one of the annular chambers where the pressure of the several streams is equalized, and a second set 50 of conduits which receive motive fluid after it passes through the reversed stage and discharge it into a second annular chamber where the pressure of the several streams is equalized.

55 11. An elastic fluid turbine comprising a plurality of stages, some of which are partial flow and the remainder total flow, one of the total flow stages being reversed with respect to the others, nozzles for the partial flow 60 stages which convert the available stage pressure into velocity, nozzles for the total flow stages that convert only a portion of the available stage pressure into velocity, wheel and intermediate buckets for the partial flow stages that abstract the energy of the

fluid stream without imparting velocity thereto, rows of intermediate and wheel buckets for the total flow stages that alternately convert the pressure of the fluid into velocity and abstract it, conduits for conveying fluid past the reversed stage to the discharging devices of said stage, and other conduits which receive the fluid exhausting from said reversed stage and convey it past said stage to the discharging devices of another total flow stage.

70 12. An elastic fluid turbine comprising a casing, diaphragms for dividing the casing into stages, one of said stages being reversed with respect to the others to reduce the axial thrust, a set of conduits formed in the casing which convey fluid past the reversed stage and deliver it to the discharging devices thereof, a second set of conduits also formed in the casing which receive fluid exhausting from the reverse stage convey it past said stage and deliver it to the discharging 75 devices of a stage of lower pressure.

80 13. An elastic fluid turbine comprising a casing, diaphragms for dividing the casing into stages, wheel buckets therefor one of which acts in a reversed manner with respect to the others, an internal projection on the casing having shoulders which support diaphragms, independent annular chambers 85 formed in the casing which supply motive fluid to certain stages, a set of conduits formed in the projection between the shoulders and the outer wall of the casing which convey motive fluid to one of the annular chambers and its stage, and a second set of conduits also formed in the projection between the shoulders and the wall of the casing which convey motive fluid from the last mentioned stage to another annular chamber 90 and to its stage.

100 14. An elastic fluid turbine comprising a casing, diaphragms for dividing the casing into stages, one of which is reversed with respect to the others, an internal projection on the casing having shoulders of different diameters formed on the projection to support diaphragms, the diaphragm of higher pressure being smaller than the one of lower pressure, conduits and annular chambers formed in the projection, discharging devices receiving fluid from the chambers, and wheel and intermediate buckets receiving fluid from said devices.

110 15. An elastic fluid turbine comprising a plurality of high pressure stages working on the partial flow plan, low pressure stages working on the total flow plan, nozzles for the high pressure stages, rows of wheel buckets therefor, nozzles for the low pressure stages, rows of wheel buckets therefor which alternately convert the pressure of the fluid into velocity and extract it, the number of rows of wheel buckets being greater in the low pressure stages than in 115 120 125 130

- the high, and means for causing the elastic fluid to flow in a given direction through one low pressure stage and in the reverse direction through another.
- 5 16. In an elastic fluid turbine, the combination of a casing, a bucket wheel mounted therein, a plate located adjacent to the wheel to prevent the fluid exhausting therefrom from rebounding on an adjacent surface and 10 striking the wheel, and a conduit receiving the exhaust from the wheel.
17. In a turbine, the combination of a plurality of stages each provided with a nozzle, and wheel and intermediate buckets, one or 15 more of said stages constructed and arranged to exert a thrust in the downward direction and one or more of said stages constructed and arranged to exert a thrust in the upward direction which partially balances the com- 20 bined effect of the weight of the moving parts and the said downward thrust, a vertical shaft carrying the wheel buckets, and a step-bearing that takes up the remaining thrust and weight on the shaft.
- 25 18. In a turbine, the combination of stages each of which is provided with a nozzle and wheel and intermediate buckets for abstracting the velocity of the fluid by successive op- erations, the said stages being balanced as to end thrust, stages each of which is provided 30 with a nozzle and wheel and intermediate buckets acting by impact and reaction to convert the energy of the motive fluid into work, the said stages being reversed with respect to each other so that the thrust of one 35 balances the other to a greater or less extent, and a means for taking up the unbalanced thrust.
19. A turbine comprising a stator, a compound rotor consisting of a disk wheel and 40 drums, means for introducing the operating fluid to the operative surface of the rotor, means for causing the whole of such fluid to flow in one direction along a portion of the length of the operative surface of the rotor, 45 means for causing the whole of such fluid to flow in the reverse direction along another portion of the length of the operative surface of the rotor, and means for conveying such fluid away from the turbine. 50

In witness whereof, I have hereunto set my hand this 18th day of January, 1907.

WILLIAM L. R. EMMET.
